(57) **CLAIM**

The ornamental design for a bird feeder having a seed hopper, substantially as shown and described.

DESCRIPTION

FIG. 1 is a top perspective view of a bird feeder having a seed hopper showing my new design;

FIG. 2 is an exploded top perspective view thereof;

FIG. 3 is a bottom perspective view thereof;

FIG. 4 is an exploded bottom perspective view thereof;

FIG. 5 is a front elevational view thereof, a rear elevational view thereof being the same as the front elevational view shown in FIG. 5;

FIG. 6 is an exploded front elevational view thereof, an exploded rear elevational view thereof being the same as the exploded front elevational view shown in FIG. 6;

FIG. 7 is a left elevational view thereof, a right elevational view thereof being the same as the left elevational view shown in FIG. 7;

FIG. 8 is an exploded left elevational view thereof, an exploded right elevational view thereof being the same as the exploded left elevational view shown in FIG. 8;

FIG. 9 is a top plan view thereof;

FIG. 10 is an exploded top plan view thereof;

FIG. 11 is a bottom plan view thereof; and,

FIG. 12 is an exploded bottom plan view thereof.

The broken lines and portions contained within are not claimed.
